PACKING STAND ASSEMBLY

Gerald C. Paxton, Sanger, Calif., assignor to General Nailing Machine Corporation, Sanger, Calif., a corporation of California

Application October 2, 1948, Serial No. 52,540

7 Claims. (Cl. 209—122)

1

This invention relates to, and an object is to provide, a packing stand assembly to support loaded field lugs or boxes of fruit in a position, at predetermined stations, for ready and convenient access by an operator who manually removes the fruit from each field lug and packs such fruit, by grade, in shipping boxes.

While the above packing stand assembly is designed especially for the grape packing industry, it is equally as useful in connection with the packing of other fruits or vegetables.

Another object of the invention is to provide a packing stand assembly which embodies a novel conveyor and supporting arrangement operative to feed loaded field boxes, one at a time, to each packing station and to then support each box in a position adjacent but clear of the corresponding packing stand so that the operator, with a minimum of effort, can effect transfer of such box from the support to the packing stand after unloading of the previous box on said stand.

An additional object of the invention is to provide a packing stand assembly which embodies, in each stand, a novel box discharge and carry-off structure; such structure being formed in a manner such that each box, after being unloaded, is easily manually tripped from the stand, and thence slides onto a carry-off conveyor.

A further object of the invention is to provide a packing stand assembly which is arranged to accelerate the handling of fruit, from supported field boxes, for the purpose of packing for shipment; the entire assembly being designed to minimize manual effort, and to expedite the process.

It is also an object of the invention to provide a packing stand assembly which is of simplified construction, embodying few moving or driven parts, and thus requiring a minimum of maintenance or repair.

A further object of the invention is to provide a practical and reliable packing stand assembly, and one which will be exceedingly effective for the purpose for which it is designed.

These objects are accomplished by means of such structure and relative arrangement of parts as will fully appear by a perusal of the following specification and claims.

In the drawings:

Fig. 1 is a fragmentary plan view of the packing stand assembly, showing two of the packing stations.

Fig. 2 is a cross section on line 2—2 of Fig. 1. Referring now more particularly to the char-

acters of reference on the drawings, the packing stand assembly comprises an elongated, upstanding main frame, indicated generally at 1, including rear posts 2, front posts 3, and end beams 4.

At longitudinally spaced points along the frame 1, there are separate packing stations, each attended by an operator; the present embodiment illustrating two such stations, identified in Fig. 10 as "Station A" and "Station B."

To the rear of the packing stations, and on top of the frame 1, there is a longitudinal, box conveyor which comprises the following structural arrangement:

15 The main frame 1 is fitted, on top and at the rear, by a longitudinal back rail 5 provided, on the front side, with a plurality of spaced rollers 6; such rollers thus being in a longitudinal row for box support, as will hereinafter appear.

20 The rollers are end flanged, as at 7, at their inner ends, whereby to prevent supported boxes from shifting into engagement with the back rail 5.

Forwardly of the longitudinal row of rollers 6, the main frame 1 is fitted with a pair of longitudinal beams 8 in adjacent but spaced apart parallel relation; there being small rollers 9 journaled between said beams to support the upper run 10 of an endless chain; such upper run being driven in the direction indicated by the arrow in Fig. 1.

30 The upper run 10 of the endless chain is disposed in a horizontal plane somewhat higher than the upper working surface of the rollers 6 whereby a transversely disposed box 11 rests on said rollers 6 and upper run 10 at a rearward and downward incline. The upper run 10 of the endless chain engages the bottom of each rearwardly inclined box 11 slightly beyond its center in a rearward direction, so that such box may be easily and conveniently tilted forwardly by hand; i. e. in the direction indicated by the arrow in Fig. 2.

35 The boxes 11, which are field boxes or lugs filled with fruit, are fed onto the longitudinal conveyor, comprised of the rollers 6 and upper run 10, from one end of said conveyor, and thence travel with the same to the respective packing stations. As the boxes advance one reaches Station B and abuts a fixed stop 12, and thence remains at said station with the upper run 10 of the chain slipping beneath the box. As long as such box remains at Station B on the conveyor, it actuates a teeter-bar-type stop unit 13 which stops the next following box 11 at Station 50 A; the upper run 10 of the endless chain then

likewise slipping below said next following box. In this manner a filled box is maintained on the conveyor at each of the packing stations at all times, and preparatory to movement of each such box onto the corresponding packing stand, hereinafter described.

The endless chain which includes the upper run 10 turns at the ends of the main frame 1 about direction-changing sprockets (not shown) enclosed in a housing 14, one sprocket including a drive shaft 15 to which a suitable driving motor unit is connected.

The endless chain is disposed so that its lower run 16 returns lengthwise through the frame 1 at a relatively low point and in a vertical longitudinal plane some distance ahead of the upper run 10, for the purpose hereinafter described. The lower run 16 of the endless chain is supported by rollers 17 carried between longitudinal beams 18 fixed in the main frame by frame parts 19.

As the packing stand at each packing station is identical, a description of one such stand will suffice for all:

At each packing station the main frame 1 is fitted, on top thereof, with a pair of transverse frame bars 20 which extend from the adjacent longitudinal beam 8 first upwardly a short distance and thence at a forward and downward incline to connection with a top front rail 21 on said main frame 1. The frame bars 20 are spaced apart, in parallel relationship, a distance slightly greater than the endwise width of each box 11, and are disposed to opposite sides, in symmetrical relation, of a box stopped above on the conveyor for manual withdrawal onto the packing stand.

When the operator desires a filled box 11 on the packing stand, the stopped, rearwardly inclined box above on the conveyor is grasped at the front and pulled slightly forwardly, causing the box to tilt downward, whence it travels forwardly and endwise on rollers 22 carried on a cross shaft 23 between the bars 20 at a point near the adjacent beam 8.

As each such box runs forwardly on the rollers 22, it engages and travels by gravity down slide plates 24 which project laterally inwardly from the bars 20.

The box continues to advance endwise until it abuts the front rail 20, then being in the position shown in dotted lines in Fig. 2.

With each box on the packing stand in such position, i. e. inclined forwardly and downwardly, the fruit is within easy reach of an operator standing at the station; the fruit being lifted from such box, manually graded, and placed into a shipping box on an adjacent stand (not shown). All reject or cull fruit is dropped into a cull hopper 25 which projects outwardly from the front rail 21 below the same. The cull hopper 25 delivers, within the main frame 1, onto an endless longitudinal cull conveyor 26, which runs in a trough 27. The cull hopper 25 includes a swing gate 28 to control the flow of culled fruit in the hopper 25 onto the cull conveyor 26.

When each box, on the packing stand, has been unloaded, it is easily discharged and carried off as follows:

With the exception of a relatively narrow, continuing part or extension 24a, which extends to the front rail 21 from one slide plate 24, said slide plates terminate, as at 29, a distance from the front rail 21 slightly greater than the height of each box. Each box, as initially advanced onto the packing stand, is shifted laterally by an in-

wardly facing, downwardly inclined cam plate 30 on the bar 20 opposite the slide extension 24a, into engagement with the other frame bar 20 so that in full advanced position said extension 24a supports the front end portion of the box at one side. Such lateral shifting of the box is possible by reason of the fact that the bars 20 are spaced, as previously described, a distance somewhat greater than the end width of each box.

After each box 11 is unloaded, the operator grasps the box at the rear end and swings such box upwardly and forwardly in the direction indicated by the arrow, from the dotted line position to the broken line position, as in Fig. 2; the front rail 21 serving as a fulcrum over which the box is turned endwise to inverted position. As the box inverts it slides, with the normally open top undermost, between the front rail 21 and the ends 29 of the slide plates 24; the box being shifted slightly laterally by hand, to clear the slide extension 28.

As the inverted box passes through the opening between the front rail 21 and ends 29 of the slide plates 24, it is received by spaced slides 30 which extend at a rearward and downward incline above the cull conveyor 26. As a result any fruit, leaves, or debris remaining in the box falls between the slides 30 onto the cull conveyor 26 to be carried away.

From the spaced slides 30, the inverted box moves by gravity on a continued rearward and downward path; being turned downward by an upstanding, forwardly concave deflector 31 to an endwise position, resting on the lower run 16 of the endless chain. Once the box is disposed endwise on the lower run 16 of the endless chain, it is conveyed longitudinally through the main frame 1 toward one end thereof for discharge; being maintained in proper position on said run by an upper longitudinal guide 32 above the deflector 31, engaging one side of the box near the top, and transversely spaced lower longitudinal guides 33 on opposite sides of the box near the bottom. Each box normally inclines rearwardly, when on the lower run 16 of the endless chain, and rests—adjacent the top—against the upper longitudinal guide 32.

With the described packing stand assembly, a loaded box is constantly maintained above each packing stand for ready access by the operator, and for manual displacement to slide downward onto the packing stand.

After unloading of each box, its discharge and carry-off results from a further simple manipulation of the box which requires no great effort on the part of the operator; the discharge and carry-off being accomplished quickly to the end that the next loaded box may be brought onto the stand for attention. Additionally, as the boxes are inverted above the cull conveyor 26, each box is clean when it is fed out of the frame 1 by the run 16.

The packing stand assembly is thus a convenient, practical, and reliable structure for its intended purposes.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A packing stand assembly comprising an upstanding frame, a box support on the frame spaced rearwardly of the front thereof, another box support on the frame in front of said rear support, said support being adapted to receive boxes thereon lengthwise toward the front and for transfer from the rear to the front support, said front support including a forwardly and downwardly inclined slide having an opening in its lower end portion through which a box may pass endwise only, and means in the frame to receive each box passed through said opening; said rear support including a power driven conveyor, and stop means to locate a box on said support in a predetermined position for transfer to the front support; said conveyor extending transversely of the direction of box transfer between the supports, and comprising a conveyor run supporting each box from below intermediate its ends, and a row of rollers lying in a lower horizontal plane than the conveyor run supporting each box from below at the rear end of the box.

2. A packing stand assembly, as in claim 1, in which said conveyor run engages each box close to its center of gravity in a rearward direction.

3. A packing stand assembly, comprising an upstanding frame, a box support on the frame rearwardly of the front thereof, a front support on the frame in position for direct transfer of a box lengthwise from the rear support, the front support including a forwardly and downwardly inclined slide, a box stop at the lower end of the slide, there being an opening in the lower portion of the slide through which a box may pass endwise only, a downwardly opening chute extending in the frame at a downward and inward incline from adjacent and below said opening, a cull conveyor in the frame running below the open chute, the latter extending across the conveyor, and a box carry-off conveyor rearwardly of and parallel to the cull conveyor in position to receive each box discharged from said open chute.

4. A packing stand assembly comprising an upstanding frame, a box support and conveyor unit spaced rearwardly from the front of the frame in parallel relationship, said box support and conveyor unit including a longitudinal row of rollers at the rear and the upper run of an endless conveyor spaced in front of said row of rollers, each box extending lengthwise transversely of the support and conveyor unit with said upper run adjacent the center of balance of said box lengthwise thereof, a front support on the frame in position for direct transfer of a box lengthwise from the rear support and conveyor unit, the front support including a forwardly and downwardly inclined slide, and a box stop at the lower end of said slide.

5. A packing stand assembly comprising an

upstanding frame, a box support on the frame, there being an opening associated with the support to permit a box on the support to be projected endwise through and to a point below the support, a downwardly and inwardly inclined chute below the support and adapted to receive and guide a box projected from the support, such chute including slide bars laterally spaced apart to form an open space therebetween whereby refuse from an inverted box on the slide bars will fall through said space, and a refuse collector disposed below said space.

5 6. A stand assembly as in claim 5 including a continuously moving conveyor disposed at a point below and rearwardly of the inner end of the chute, and means associated with the chute and frame and effective to upend a box leaving the chute and deposit it edgewise on the conveyor.

10 7. A packing stand assembly comprising an upstanding frame, a rear box support on the frame, a front box support in front of said rear support and adapted to receive a box when moved laterally of its length from said rear support, the front support including side guide members spaced apart a distance greater than the length of a box, and leaving an opening therebetween, a box stop member defining the front end of said opening, downwardly and forwardly inclined box-supporting plates extending forwardly over said opening along the sides thereof from the rear end of the support and terminating at their forward end a distance from the stop member less than the width of a box but greater than the height of such box, a relatively narrow forward projection of one slide plate extending alongside the adjacent side member to the stop member and leaving a space between said extension and the opposite side member whose extent is slightly greater than the length of a box, and an element on the other slide plate to shift a box lengthwise and against said adjacent side member upon such box being pulled from the rear support onto the front support, whereby said box when so shifted will be supported over said opening by said slide plates and the extension, and a chute under the opening in position to receive a box when tilted for sidewise passage through the portion of the opening in front of the slide plates.

GERALD C. PAXTON.
